UNITED STATES PATENT OFFICE.

SAM DEAN, OF LOWELL, MASSACHUSETTS.

STOP-MOTION FOR SPINNING AND TWISTING MACHINES.

No. 892,982.

Specification of Letters Patent.

Patented July 14, 1908.

Application filed August 5, 1907. Serial No. 387,195.

To all whom it may concern:

Be it known that I, SAM DEAN, a subject of the United Kingdom of Great Britain and Ireland, residing at Lowell, in the county of 5 Middlesex and Commonwealth of Massachusetts, have invented a certain new and useful Improvement in Stop-Motions for Spinning and Twisting Machines, of which the following is a specification.

10 This invention relates to stop-motions for spinning and twisting machines, in which a rising and falling plate or rail is used to control the laying of the yarn on the bobbin, spool or other tube, and is particularly intended for worsted cap-spinning and twisting machines.

15 In cap-spinning machines, such as are represented in the drawing, the caps are supported on stationary spindles and the bobbins or spools are turned on the spindles by the usual means (not shown) and the bobbins are raised and lowered by a lifter-plate to put successive layers of yarn on said bobbin, the lower limit of this vertical traverse 20 increasing until the predetermined quantity of yarn is placed on the bobbin, the yarn being guided to its place on the bobbin by the bottom edge of the cap in the usual manner. The lifter-plate is controlled by the usual 25 vertical guide-rods, which pass through transverse rails which form a part of the frame of the machine in the usual manner and the stop-motion device is put in operation to stop the machine by the descent of 30 one of these guide-rods to a predetermined 35 distance.

The object of this invention is to stop the machine as soon as the bobbin or other yarn-receiver has taken on a predetermined quantity of yarn, instantly, and to prevent the machine from being started too suddenly in such a manner as by the shock of starting to break the yarn.

40 Said invention consists in the devices and combinations hereinafter claimed.

In the accompanying drawing, Figure 1, is a front elevation of so much of a cap-spinning machine provided with my improvement as is necessary for the understanding of 45 the same; Fig. 2, is a vertical section from front to rear of the same on the line 2-2 in Fig. 1.

A indicates the frame; a, the bottom rail; 50 a¹, the spindle-rail; B, stationary spindles supporting the caps b; C, the tubes or shells provided with whirls c, which are rotary on

the spindles B, being driven by bands (not shown) connecting said whirls to the band-cylinder D; E, the lifter-plate; e, the lifter-rods; F, bobbins, carried by the tubes C; 60 which rest on said lifter-plate; e¹ the longitudinally reciprocating chain rod which, through chains e² and pulleys e³ actuates the lifter-plate; the twist-wheel G; twine-wheel G¹, fast on the main-shaft D¹ or cylinder-shaft, the belt g connecting said twine-wheel 65 to said twist-wheel; a pinion g¹ fast on the shaft of said twist-wheel and engaging a gear i fast on the shaft i¹ of the bottom front roll I; the front rolls I I¹; the carriers J J¹; the 70 back rolls K K¹; the fast pulley d and loose pulley d¹ on the main shaft D¹;—these parts are all of the usual construction and operation.

Usually the non-rotary horizontal shipper-rod L carrying a belt-fork l² or belt-guide is formed in a single piece or section and carries a nut l³ engaged by a horizontal screw M which may be turned by a crank m to move said shipper-rod longitudinally to 75 ship the belt D² from one of the pulleys d d¹ to the other, to stop or start the machine. I retain these parts, but I make the shipper-rod in two aligned sections, l l¹, each of which is provided with a hook or coupling-counter-part l⁴ l⁵ adapted to engage the hook of the other part, so that by turning the screw M in the proper direction I can shift the belt 80 D² from the loose pulley to the fast pulley, 85 to start the machine.

It will be understood that the lower limit of the vertical traverse of the lifter-plate descends, as the yarn is wound upon the bobbins from the bottom to the top of said bobbins.

I provide means by which as soon as the bobbins are filled to a predetermined height, the hooks l⁴ l⁵ will be uncoupled and the section l¹ of the shipper-rod which carries the belt-fork will be moved longitudinally 90 by a spring,—represented as a helical spring l⁶ surrounding said section l¹ and compressed between a stationary bracket a² on the frame A and a collar l⁷ fixed on said section l¹ and will shift the driving belt D² from the fast pulley d to the loose pulley d¹.

I pivot a lever N at n on the frame near the inner end of the section l and on the rear end of this lever I support the guide l⁸ in which said section slides. The other or front 100 end of said lever N reaches in front of the frame A and has jointed to it at n¹ a link n²

which passes loosely down through a bracket e^4 which extends from one of the lifter-rods e and is rigidly secured thereto. The lower end portion of the link n^2 is screw-threaded at n^5 to engage a nut n^3 and check-nut n^4 , arranged below the bracket e^4 and adapted to be struck by said bracket in its descent to a predetermined point, at which the nut n^3 is adjusted by turning on the screw n^5 .

10 When the link n^2 is pulled down by the bracket e^4 , the lever N is rocked to raise the guide l^8 and thereby to lift the hook l^4 out of engagement with the hook l^5 whereupon the section l^1 of the shipper is thrown by 15 the spring l^6 outward until the collar l^7 strikes the frame A and transfers the belt from the fast pulley d to the loose pulley d' allowing the machine to stop instantly.

When it is desired to start the machine 20 after doffing, placing empty bobbins on the tubes C and adjusting the builder-motion by the usual means to the starting point, the screw M is turned to move the hook l^4 towards the belt-fork, causing the inclined 25 under surface l^{10} of the hook l^4 to ride over the correspondingly inclined upper surface l^{11} of the hook l^5 until the point or free end of said hook l^4 strikes a stop projection l^{12} and said hook l^4 drops into engagement with 30 the hook l^5 , restoring the lever N and link n^2 to normal position and the screw M is then turned in the opposite direction to draw the driving belt D^2 slowly from the loose pulley d' to the fast pulley d and starting the machine without shock.

I claim as my invention:—

1. The combination in a twisting or spinning machine of a driving shaft, a fast pulley and a loose pulley both on said shaft, a 40 shipper-rod formed in two sections, each provided with a hook adapted to engage the

hook of the other section, a lever, a bearing for one of said sections supported on said lever, a belt-fork carried by the other of said sections, a lifter-plate, means for giving the same a vertical traverse, a lifter-rod, movable with said lifter-plate, connecting means between said lifter plate and said lever, adapted to rock said lever and to uncouple said sections by the descent of said lifter-rod, a spring to move the belt-fork carrying section of said shipper rod from the fast pulley to the loose pulley and a driving-belt guided by said fork.

2. The combination in a twisting or spinning machine of a driving-shaft, a driving-belt, a fast pulley and a loose pulley both on said shaft, a shipper-rod formed in two sections, each provided with a hook adapted to engage the hook of the other section, a lever, a bearing for one of said sections supported on said lever, a belt-fork carried by the other of said sections and guiding said belt, a lifter-plate, means for giving the same a vertical traverse, a lifter-rod movable with said lifter plate, a bracket carried by said lifter-rod, a link jointed to said lever and passing loosely through said bracket, an adjustable stop carried by said link below said bracket and adapted to be struck by said bracket in the descent of said lifter-rod to a predetermined extent, to rock said lever and to uncouple said section, and a spring to move the belt-fork carrying section of said shipper from the fast pulley to the loose pulley.

In testimony whereof, I have affixed my signature, in presence of two witnesses.

SAM DEAN.
